[57] CLAIM

The ornamental design for the bucket caddy for tools, as shown and described.

DESCRIPTION

FIG. 1 is a perspective view of the bucket caddy for tools showing my new design, the broken line showing of the tools for illustrative purposes only and forming no part of the claimed design;

FIG. 2 is a top plan view thereof;

FIG. 3 is a bottom plan view thereof;

FIG. 4 is a cross-sectional elevational view thereof taken along line 4—4 of FIG. 2; and,

FIG. 5 is a cross-sectional elevational view thereof taken along line 5—5 of FIG. 2.
